METHOD AND APPARATUS FOR X-RAY WORK.

Application filed June 16, 1921. Serial No. 477,905.

This invention relates to a method and apparatus for conducting X-ray examinations, and is particularly directed to a method for examining the foot of a patient and to a machine for effecting such examination.

It is well known that in the radiographic examination of the feet of patients that the results of such examinations are usually unsatisfactory as they merely examine the foot in its unloaded or free condition. There has been a long felt want for a machine by which it is possible to examine the foot of a patient not only in the unloaded condition or free from the weight of the body, but also while the foot is active in sustaining its share of the weight of the body. It is also obvious that it is imperative, for a properly conducted examination, to provide a machine for the above outlined purposes by which it is possible to examine the foot from any one of a great number of angles, that is to say, look through the foot directly downwardly and also sidewise through the foot so as to examine the articulation or association of the bones of the foot while they are sustaining the weight of the patient. It is therefore a primary object of this invention to provide an X-ray machine which will fulfill the above outlined requirements.

Objects of this invention are to provide an X-ray machine for examining the foot of a patient either encased in or free of shoes; to provide a machine in which the examination of the foot is made while such foot is under the normal stresses imposed thereon, that is to say, while the foot is supporting its part of the weight of the patient; to provide a machine in which the examination may be continuously conducted while the weight is shifted or varied so as to accurately ascertain the relative positioning of the bones and joints of the foot under varying or uniform pressure; and to provide such a machine so arranged that both the patient and operator may simultaneously examine the foot so that defects may be freely discussed during the examination.

Further objects are to provide an X-ray machine for examining the foot of a patient in which provision is made for viewing the bones of the foot at several different angles whereby it is possible to see through the

foot looking directly down thereon and also to examine the arch of the foot by looking horizontally across the foot or through the foot in either direction; and to provide such a machine arranged to allow this examination without necessitating changing the position of either the operator or of the patient.

Further objects are to provide an X-ray machine for examining the foot of a patient in which provision is made for pointing out and indicating upon the fluorescent screen the defects, or various points that it is desired to call to the attention of the patient; to provide such a machine arranged for either fluoroscopic inspection or for the production of permanent plates; and to provide such a machine so organized that unskilled operators may use it without danger of any kind and with absolute assurance of the results.

Further objects are to provide an X-ray machine in which provision is made for rotating the tube so that one tube may be employed to examine the foot of a patient from any one of a plurality of angles; to provide a series of mirrors so arranged that they will cooperate with the tube in any one of its many positions and direct the visible rays to a suitable location for both the patient and the operator; and to provide such a machine so organized that the cooperation of the mirrors and of the tube is assured and is automatic while still permitting manual control of either the tube or of the mirrors at the will of the operator.

Further objects are to provide an X-ray machine for examining the foot of the patient in which eye pieces or eye cups are provided for the operator and for the patient, and if desired, for an additional observer; to provide means for adjusting the height of the eye pieces to accommodate patients of varying heights; and to provide means whereby a sanitary condition of eye cups may be maintained, as for example, by providing removable sanitary cups so that after one use thereof the cups may then be discarded and a new cup or a new set of cups substituted.

Further objects are to provide a method for examining the foot of a patient, either

while said foot is bare or while it is enclosed within a shoe; to provide a method for conducting such examination while the foot is loaded, that is to say, bearing weight; and to provide a method for examining the articulation of the bones of the feet while the weight of the body is thrown upon the balls of the feet.

An embodiment of the invention is shown 10 in the accompanying drawings, in which:

Fig. 1 is a side elevation of the apparatus.

Fig. 2 is an end elevation thereof.

Fig. 3 is an end elevation of the apparatus 15 with the upper hood removed.

Fig. 4 is a plan view of the structure shown in Fig. 3.

Fig. 5 is a side elevation of the structure shown in Fig. 3.

Fig. 6 is a detail of the sanitary eye cup.

20 Fig. 7 is an end view of a further form of the invention showing a portion of the cabinet removed to illustrate the interior construction.

Fig. 8 is a side elevation of the device 25 shown in Fig. 7.

Figure 9 is a diagrammatic end view showing the positions that the mirrors, tube, and the particular screen then in use, occupy, and also showing the path of the X-rays and 30 of the visible or light rays.

Figure 10 is a plan view of one of the mirrors detached.

Figure 11 is a fragmentary view showing 35 one of the spring catches in the position it occupies when it co-operates with the supporting lever of the tube.

The device comprises a boxlike structure 40 having a permanent base portion and a removable top or hood 1. The base portion is composed of side members 2 and 3 and a pair of top members 4 and 5 arranged at different levels as may be seen from Figs. 1 and 5 so as to provide steps for the oncoming patient. The top 4 which is at the higher level has 45 cut out portions adjacent its front, leaving a central tongue 6 which extends to the front of the machine and is secured thereto. This tongue is the portion of the apparatus upon 50 which the patient places his foot during the examination. The X-ray tube is adjustably mounted so that it may be positioned beneath this panel or tongue 6 in a manner hereinafter to be described.

55 The removable top or hood 1 is composed of side members 7 which converge towards their upper portion and with a pair of slanting rear members 8 and a slanting front member 9. It is to be noted from an inspection of Figs. 1, 4 and 5 that the rear portion of the hood has a cut out formation which is secured by an upright panel 10 which extends from the rear upper edge of the slanting piece 11 to the plane of the 60 members 8. It will further be noted that the slanting hood compels the patient to lean 65

forward while he inspects his feet, thereby placing weight directly upon the balls of the feet and causing the bones to assume the relative positions they normally occupy when sustaining the weight of the body. 70 Triangular side portions 12 join this upright panel and the rear portions 8 and complete this portion of the hood. The top of the hood is formed of a slanting substantially rectangular top member 13 which is provided with openings 14 and 15 adapted to receive eye pieces. If desired, shutters may be resiliently and slidably mounted beneath the top portion 13 and may be pulled out 75 when it is desired to use either of the peep holes, such shutters being adapted to close the unused peep holes and thereby keep the interior of the hood relatively dark. The hood is provided with a rectangular boxlike structure 16 which opens into the hood and is open at its upper end. A similar slightly larger boxlike member 17 telescopes the portion 16. Suitable guiding rods 18, 80 extending upwardly upon opposite sides from the base portion and corresponding telescopic members 19 extending downwardly from the upper portion and provided with thumb nuts 20, are adapted to lock the adjustable members in the desired position. The upper member 17 has a rectangular 85 closed top 21 which is provided with an eye piece 22 through which the patient may look. The width of the boxlike structure is such that the patient may look either downwardly or to opposite sides of the hood portion and 90 see the reflection in the particular mirror in use. 95

In order to provide proper ventilation for the apparatus, the base portion is provided with openings 23 upon opposite sides. These 100 openings communicate with a blackened box 24 which is provided with a series of blackened baffle plates 25 adapted to allow circulation of air but prevent the passage of light therethrough. 105

The location of the generating apparatus and of the control apparatus may conveniently be as follows. If direct current is furnished, a converter 26 may conveniently be 110 positioned beneath the floor portion 5. The main transformer 27, electrically connected thereto and supplying the tube with high tension current, may be located beneath the floor portion 4. A relatively small transformer 28 may be located adjacent the main transformer and may supply the filament current of the Coolidge tube. Upon the front of the apparatus, a main switch arm 29 extends outwardly therefrom and controls the main or supply circuit for the entire apparatus. A starting rheostat arm 30 extends through an arcuate slot 31 and controls the converter 26. A rheostat knob 32 controls the current supplied the filament of the Coolidge tube and may be provided with a 115 120 125 130

pointer 33 adapted to indicate upon a suitable scale 34 the milliamperes flowing in the filament circuit for the particular setting of the rheostat.

6 One of the sanitary eye pieces previously mentioned is illustrated in section in Fig. 6. It comprises a base portion 35 provided with suitable apertures 36 whereby it may be secured adjacent the appropriate opening. It 10 is provided with a groove 37 into which the contracted portion of a sanitary eye cup 38 is adapted to be slipped. It is understood that these cups 38 may be discarded after one use and a new cup readily inserted within 15 in the slot 37. In this manner, the patients have no hesitancy in placing their faces in contact with the cups while the examination is in progress.

1 A foot switch 39 may be connected by suitable 20 flexible conductors 40, carried in a cable, for instance, with the primary circuit in the main transformer 27 and may thereby control the operation of the X-ray tube. The electrical connections of this machine are 25 closed in greater detail in the co-pending application of Matthew B. Adrian for X-ray apparatus, Serial No. 477,904, filed June 16, 1921.

1 The X-ray tube 41 is of the Coolidge type 50 and is pivotally mounted so that it may be swung to any one of a plurality of positions, the three main positions being directly beneath the foot and upon the right or left side thereof. A convenient way of carrying 55 the tube is by means of a swinging lever 42 which is rigidly carried upon a shaft 43 provided with external operating crank 44. This arm is adapted to be locked in any one of the three main positions by means of 60 spring catches 45 and may further be locked in any intermediate position by means of the set screw 46. These catches 45 may be seen in Figures 1, 2, 3, 4, 5, 8 and 12. It is to be noted that a plurality of these catches, which 65 consist of a spring pressed plunger and an operating external knob, may be provided about the face of the front portion of the machine. It is obvious that these catches may co-operate with the tube supporting 70 lever 42 or 47, (depending upon which modification is in use), and may therefore hold the tube in any one of several positions of adjustment. It is also to be noted that another manner of locking the tube in these 75 various positions of adjustment may be secured by means of the set screw 46 which passes thru and is threaded to a stationary portion of the machine and bears at its lower end upon the shank 43 of the operating crank 80 85 90 95 100 105 110 115 120 125 130 44 in an obvious and well known manner. The outer portion of the arm is provided with a horizontal part 47 upon which a box 48 is mounted. Within this box 48 a pair of supports 49 carry the lead glass casing 50 within which the tube 41 is mounted, the

lead glass casing of course being provided with a cut out or open portion 51 to allow the free passage of the X-rays. The box 48 is provided with the ventilators 52 and 53 similar to the ventilators previously described but of small size. The box is preferably painted with lead paint throughout its entire portion except for a relatively small circular area directly over the opening 51 of the lead glass shield 50. Spring reels 53' 70 75 resiliently hold the conductors 54 in taut condition while allowing motion of the tube with corresponding unreeling of the conductors. These conductors supply the filament current and also connect one side of the high tension transformer 27. The other conductor 55 which connects the other end of the tube with the high tension transformer circuit is resiliently held taut by means of the spring reel 56 located upon the floor of the compartment and adjacent the other end of the tube so as to secure adequate spacing for the high tension leads.

1 The inner walls 57 and 58 of the bottom portion, which extends upwardly a material distance from the floor portion 4, are provided with guide ways within which slide the fluorescent screens 59 and 60, such screens being adapted to be withdrawn rearwardly and sliding in the grooves 61 and 62 formed in the floor portion 4. These screens are adapted to carry, when desired, suitable plates for radiographic work, or additional slides for carrying suitable plates may be substituted for the fluorescent slides. For 100 examining the foot with the tube in the position shown in Fig. 5 a fluorescent screen is removably carried by the panel 11. This fluorescent screen is, of course, suitably protected and is carried upon the upper side of the panel unless such panel is made of material transparent to the visible rays. Another way of mounting this fluorescent screen would be to substitute it for the panel 11 and allow the screen to thereby replace such panel. It is, of course, understood that these fluorescent screens are suitably protected and mounted.

1 A pair of mirrors 63 and 64 are arranged 115 within the base portion and are hingedly mounted at 65 and 66 adjacent opposite sides thereof. These mirrors are normally supported at about 45° by any suitable means, as for example, adjusting screws 67 and 68, and are provided upon their under surface with cam members 69 and 70, respectively, of insulating material. When the tube is rotated by the operating crank 44 into the right or left hand position, one of which is indicated in Fig. 2, its housing or parts 48 contact with the corresponding cam member 69 or 70 and elevate the corresponding mirror as indicated in Fig. 2 so that the mirror is moved out of the way of the tube and allows the tube to be positioned directly

in line with the foot of the patient and opposite the other or active mirror. If any other angular adjustment of the tube is desired, it may be secured by locking the shaft 43 by means of the set screw 46 and correspondingly adjusting the mirrors by the adjusting screws 67 and 68.

In order to indicate the various defects or points to the patient, a universally mounted pointer 71 is provided and extends through the top portion 13 of the hood or upper portion of the cabinet. It is provided with a handle 72 by which the operator may indicate upon the mirrors or upon the protecting member of the central fluorescent screen the various points that he wishes to call the patient's attention to. In this manner, a very rapid examination may be made and the patient and operator may discuss with certainty the various defects illustrated. For example, any particular point may be indicated by the operator without necessitating the removal of either the operator's or patient's face from the corresponding eye cup.

Figs. 7 and 8 showing the modified form will now be described. The construction, except as indicated, is substantially similar to that previously described. In this modified form, the tube is housed within the protecting box 73 which in turn is carried upon the pivotally mounted lever 74, such lever being operated from the crank shaft 75 in the manner previously described. This lever 74 has, however, an extended portion 76 upon the opposite side of the crank shaft 75 from that occupied by the portion 74. This extension 76 carries a fluorescent screen and protecting member or plate holder, either or both of which may be removably mounted. This fluorescent screen and protecting sheath is indicated at 77. It will be seen that as the tube is rotated about the crank shaft 75 that the screen will correspondingly rotate. This construction maintains the screen and tube upon opposite sides of the object to be examined at all times. The mirrors 78 and 79 are duplicates in construction and position of the mirrors 63 and 64 previously described.

In this modified form, the cabinet and accessories are substantially the same as the previously described construction, with, however, the following main exceptions, namely, the front panel 80 is substantially vertical so as to allow room for the extension 76 and for the outer portion of the fluorescent screen and protecting sheath. The cabinet is further modified in that the portion which is recessed to receive the foot consists simply of an extended tapered housing composed of the top member 81 and the side members 82. This housing is closed throughout except for its outer rear end through which the foot of the patient is inserted. In this manner,

a free, unobstructed path is allowed for the fluorescent screen and tube to rotate about this housing for the patient's foot.

If desired, plate holders may be arranged upon the upper member 81 and upon the sides 82. These plate holders are preferably removable, and, during a fluoroscopic examination of the foot are preferably completely removed from the machine. As pointed out above, however, in place of these plate holders a single plate holder may replace the fluorescent screen or may be adapted for mounting beneath such fluorescent screen. The plate holders may be substantially similar to the screen holders, except that the plates are removably held in the holders in any well known manner.

In all of the forms of the invention, the mirrors 63 and 64 or 78 and 79, (depending upon which modification is considered), are provided with cam shaped bottom portions. This is clearly illustrated in Figures 2 and 9 for the first modification, and in Figure 7 for the second. Upon referring to Figure 9 it will be seen that when the tube is rocked to the left, for instance the cam member 69, it will contact with the then upper outer corner of the tube box. This will raise the mirror 63 from its normal position, and will move it out of the way of the tube. At the same time the tube comes in line with the screen upon the opposite side of the compartment for the foot and in line with the mirror 64. The path of the X-rays is indicated at a—a, and it will be seen that such rays pass outwardly and thru any object that is interposed between the tube and the screen finally impinging upon the screen. The screen 60 becomes luminous and emits visible rays. These visible rays pass outwardly and strike the mirror 64 from which they are reflected upwardly along slanting lines until they arrive at the eye of the observer. The path of the visible rays is indicated at b—b—in Figure 9. Also these rays are indicated by dot and dash lines in Figures 1, 4, 5, 7 and 8.

This form is particularly adapted for examining the foot at any desired angle as the screen is always accurately positioned diametrically opposite the tube. The adjusting screws or other adjusting means 83 and 84 may be manipulated to cause the mirrors to assume the proper angle to assure the reflection of the image to a point adjacent the eye cups.

It is of course understood that both the hood and bottom portion of the cabinet may be suitably lined with lead, may be pointed with a lead point, or otherwise treated to prevent the outward passage of any harmful rays.

It will thus be seen that an X-ray apparatus has been provided by which the examination of the patient's foot may be readily

and efficaciously conducted by unskilled operators. It will also be seen that the machine or apparatus is practically fool-proof and may be placed in any store, for instance, 5 where the men who operate the machine are not skilled in X-ray work.

It will also be seen that either the fluoroscopic examination or the radiographic work, that is to say, the production of plates, 10 may be had with this machine by merely properly manipulating the plates and slides.

I claim:

1. An X-ray apparatus comprising a cabinet, a tube movably mounted within said 15 cabinet, a fluorescent screen adapted to be energized by the rays from said tube, a series of mirrors for reflecting the visible rays to

the upper portion of said cabinet, and a series of members through which a patient and an operator may look. 20

2. An X-ray apparatus comprising a cabinet, a panel upon which the patient may place his foot and allow such foot to bear its share of the weight of the body, an X-ray tube positioned within said cabinet, 25 means for holding said tube in any one of a plurality of positions about said foot, a fluorescent screen adapted to cooperate with said tube, and a series of mirrors for conducting the visible rays to the upper portion of said cabinet whereby either the patient or the operator may fluoroscopically examine the foot. 30

MATTHEW B. ADRIAN.
